George H. Sanborn.

by Charles N. Gooding.
1874.

UNITED STATES PATENT OFFICE.

GEORGE H. SANBORN, OF MALDEN, MASSACHUSETTS.

AUTOMATIC TRAIN-CONTROL DEVICE.

Application filed October 8, 1921. Serial No. 506,444.

To all whom it may concern:

Be it known that I, GEORGE H. SANBORN, a citizen of the United States, residing at Malden, in the county of Middlesex and 5 State of Massachusetts, have invented new and useful Improvements in Automatic Train-Control Devices, of which the following is a specification.

This invention relates to improvements in 10 an apparatus for controlling railway trains or other vehicles of a similar character.

The object of the invention is to provide 15 an electrically operated mechanism so associated with the usual fluid pressure or air brake system of a train that if any of the common and well known traffic conditions arise within a predetermined length of track known as a block which to insure safety calls for a reduction of speed or the complete 20 stopping of the train that the same may be accomplished by the automatic setting of the brakes provided upon said train.

The invention consists in the combination 25 and arrangement of parts whereby the above objects and certain other objects hereinafter appearing may be attained as set forth in the following specification and particularly pointed out in the claims thereof.

Referring to the drawings:

30 Fig. 1 is a diagrammatic representation of a device embodying the invention.

Fig. 2 is an enlarged sectional elevation of one of the electrically operated switch mechanisms.

35 Fig. 3 is an enlarged side elevation of a shoe.

Fig. 4 is a longitudinal section through one of the valve mechanisms.

Like numerals refer to like parts throughout the several views of the drawings.

In the drawings 8 and 9 represent the rails of a single track railway line of well known construction which is divided into sections of predetermined length known as blocks.

45 The rail 8 consists of live sections 10 which may be of any desired length and short cut-out sections 11, preferably one rail length or even less which are insulated from the live sections 10 at 12. The rail 9 consisting 50 of live sections 13 equal in length of the sections 10 and short cut-out sections 14 equal in length to the sections 11, said sections 13 and 14 being insulated from each other at 55 15. Feed wires 16 and 17 connected with a suitable source of electric supply as, for example, a storage battery 7 extend along

the railway track and at one end of each live section 10 of the rail 8 said section is connected by a wire as 18 to a feed wire as 16. The live sections 13 of the rail 9 are in 60 like manner connected at one end of each section by a wire as 19 with a feed wire such as 17. A separate set of electric feed wires 16 and 17 is provided for each block and connect with a source of electric supply such as a storage battery 7. The opposite end of the live sections 10 and 13 of the rails 8 and 9 from that to which the feed wires are connected have wires 20 and 21 connected thereto which extend along the track to an electrically operated switch mechanism illustrated in detail in Fig. 2 located adjacent to one 70 end of the cut-out section 11, said wires being connected to an electro-magnet 22 forming a part of said switch mechanism. A 75 switch mechanism is provided for each cut-out section 11 and an entire block consisting of a live section 10 and a cut-out section 11 intervene between the end of the section 11 to which the wires 20 and 21 are attached 80 and the cut-out section which is controlled by the switch mechanism to which said wires 20 and 21 extend. In Fig. 1 of the drawings portions of three live sections are illustrated at A, B and C, and two intervening 85 cut-out sections e and d with switch mechanisms e' and d' for the latter.

Referring to Fig. 2, the switch mechanism e' or d' as it may be either, comprises the electro-magnet 22 previously mentioned and 90 an arm 23 consisting of suitable electric conducting material pivoted at 24 upon a base 25 of insulating material. A wire 26 connects the cut-out section 11 with the arm 23 at a point adjacent to the pivot 24 thereof. At 95 its outer end the arm 23 is provided with a contact member 27, while at an intermediate position upon said arm a block 28 constituting an armature is secured. Another electric contact member 29 is supported in 100 a suitable manner upon the base 25 and is connected by a wire 30 with the feed wire 16. When there is not sufficient electricity in the live sections 10 and 13 from which said wires 20 and 21 extend to the electro-magnet 22, the electric circuit through the switch mechanism will be broken by the separation of the contact members 27 and 29 and the electric circuit therefore through the cut-out section 11 will be opened.

Fastened to the opposite sides of the locomotive just in front of the forward lead

trucks are shoes 31 and 32 which contact with the rails 8 and 9 respectively of the railway track, said shoes being utilized when the locomotive is running ahead, while a 5 similar set of shoes 33 and 34 are mounted upon the tender of the locomotive just forward the first pair of wheels, said last-mentioned shoes being utilized when the locomotive is running backward. The shoes 31, 10 32, 33 and 34 are all constructed in a similar manner, and are illustrated in detail in Fig. 3.

Referring to said Fig. 3, the shoe 31 is mounted through the medium of pins 35 15 upon a bracket 36 which is insulated from a suitable post 37 either forming a part of or secured to the locomotive in any suitable manner. Springs 38 surrounding the pins 35 between the shoe 31 and the bracket 36 20 will act to force the shoe downwardly against the rail at about ten pounds pressure. The shoe 31 is connected by a wire 39 with a terminal 40 of a knife switch 41 located in the cab of the locomotive. An 25 other terminal 42 of the switch 41 is connected by a wire 43 with an electro-magnet 44 also conveniently located in the cab of the locomotive. A wire 45 connects the electro-magnet 44 with a storage battery 46 from 30 which another wire 47 extends to another terminal 48 of the switch 41. The shoe 32 is connected directly by a wire 49 with a terminal 50 of the switch 41. An electric light bulb 51 constituting a visible signal is connected with the wire 47. The shoe 33 is 35 connected by a wire 53 with a terminal 54 of the switch 43, while a wire 55 connects the shoe 34 with a terminal 56 of said switch. An electric light bulb 57 also constituting 40 a visible signal is connected with the wire 55.

The electro-magnet 44 previously mentioned is mounted upon a casing 58 in a position to attract an armature 59 which is slidably mounted therein. The armature 59 45 has a stem 60 projecting downwardly therefrom and adapted to slide in a bearing 61 formed in the casing 58. The armature 59 also has a pair of oppositely disposed arms 62 and 63 which project through slots 64 50 provided in the casing 58. Springs 65 and 66 interposed between the top of the casing 58 and the arms 62 and 63 respectively act to hold the armature 59 in the position illustrated in dotted lines in Fig. 1 at such times 55 as the electro-magnet is not energized. The arm 62 is connected by a link 67 with a handle 68 of an exhaust valve 69 located in a pipe 70 and connecting with a train pipe 71 forming a part of the air brake equipment 60 of the train, and which is well known to those skilled in the art. When the electro-magnet 45 is energized and attracts the armature 59 the exhaust valve 69 is held closed. When, however, the electro-magnet is de- 65 energized, the springs 65 and 66 will push

the armature 59 downwardly and open said exhaust valve. If, for any reason the handle 68 or link 67 should become broken or disconnected from the arm 62 of the armature 59 the exhaust valve 69 will also be opened 70 by a compression spring 72 which pushes against an arm 73 formed integral with the handle 68 but which is located upon the opposite end of said handle from that to which said link 67 is connected.

Connected with the train pipe 71 by a branch pipe 74 is an air reservoir 75. A check valve 76 permits the air from the train pipe to enter the reservoir 75 but prevents a return of said air to said train pipe. A pipe 77 leads from the reservoir 75 to a valve 78 located in the cab of the locomotive, said valve being provided with an operating handle 78'. Another pipe 79 extends from the valve 78 to a pressure reducing valve 80 85 preferably set at about ten pounds pressure, and from the latter a pipe 81 extends to a valve 82. The valve 82 is operated by a handle 83, which rests loosely upon the end of the arm 63 of the armature 59. A compression spring 84 suitably positioned and supported upon the casing 58 acts to push against the handle 83 and open the valve 82 when said valve is not held in its released position by the arm 63 of the armature 59 90 as illustrated in Fig. 1. If for any reason that portion of the handle 83 which rests upon the arm 63 of the armature should become broken or disengaged from said arm 63 the valve 82 will also be opened by a compression spring 85 which pushes against an arm 83' formed integral with the handle 83 but located at the opposite end thereof from that upon which the spring 84 is located. The valve 82 is connected by a pipe 86 with 95 the interior of a cylinder 87 formed in the casing 58 beneath a piston 88 located within said cylinder. The piston 88 has a stem 89 fast therein arranged to slide in a bearing 90 formed in the casing 58, and a spring 91 100 encircles the spring 89 above the piston and acts to always force said piston downwardly when there is no pressure in the cylinder 87 beneath said piston. Small bleed openings 92 and 93 are provided in the casing 58 connecting with the cylinder 87 above and below the piston 88. A valve 94 normally closed is provided connected with the pipe 86 for use when it is necessary to exhaust the air 105 quickly from said pipe and from the cylinder 87 beneath the piston 88.

In order that a graduated application of the brakes throughout the train may be made when the exhaust valve 69 is opened, regardless of the position of the automatic brake valve located in the cab of the locomotive a valve 95 is provided attached to the end of the branch pipe 70 below the exhaust valve 69. This valve 95 is illustrated in detail in Fig. 4 and comprises a cylindrical cas- 115

ing 96 in which a piston 97 is adapted to reciprocate. The piston 97 has a stem 98 projecting therefrom around which a spring 99 is located and which acts to always force 5 the piston 97 upwardly. The stem 98 is slidably mounted in a bearing 100 provided in the casing 96. V shaped openings 101 are provided in the casing 96, the narrow part of said opening being at the top and as the 10 piston is forced downwardly by the air pressing against the upper surface thereof said piston will be forced downwardly gradually increasing the area of the openings 101 and resulting in a graduated application of the 15 air brakes.

The general operation of my improved automatic train control device is as follows:— Assuming there is a train with the locomotive thereof running ahead located in the 20 live section A, said train having entered said section by reason of the fact that no train is located in the live section B which said first-mentioned train is approaching, and no train is located in the live section C, 25 or no other traffic condition exists to break the electric circuits to the magnet 22 of the switch mechanism c' said train upon entering the cut-out section c and finding the electric circuit closed therein may pass 30 therethrough without interruption. At this time conditions upon the locomotive of the train are as illustrated in Fig. 1, the electro-magnet 44 being energized and attracting the armature 59 thereby simultaneously 35 holding the train pipe exhaust valve 69 closed, and the application port through the valve 82 is closed but release ports therein are open allowing the air to escape from the pipe 81 as far as the reducing valve 80, and 40 also from the pipe 86 connecting with the under side of the piston 88. The valve 78 controlling the passage of air upon the air reservoir 75 is also closed and the piston 88 is in its lowermost position.

If, on the other hand, there is a train in the live section C, as soon as the shoes 31 and 32 of the locomotive of said train entered said section, the electric power from the rails following the line of least resistance passed through the forward wheels and axle of said locomotive short circuiting the electric current to the electro-magnet 22 of the switch mechanism c' releasing said switch and breaking the electric circuit 55 through the cut-out section c formerly held closed by said electro-magnet. At such times the instant that the shoes 31 and 32 of the locomotive of the train in the live section A enters the cut-out section c finding no electric power in said section or the connection 60 broken so that a complete circuit cannot be completed to the electro-magnet 44 upon the locomotive, said magnet will immediately release the armature 59 and the springs 65 and 66 will immediately act to push the

armature 59 downwardly thereby rocking the handle 68 of the exhaust valve 69 and opening said valve. The air in the train pipe 71 may now escape forcing the piston 97 of the valve 95 downwardly and gradually increasing the area of the openings 101 through which said air gradually escapes to the atmosphere with the result that the brakes of the train will immediately be applied and the train brought to a stop. 70 75

At the same time that the electro-magnet 44 releases the armature 59 and the latter is forced downwardly by the springs 65 and 66, the handle 83 of the valve 82 will be rocked through the medium of the springs 80 84 and 85, thereby opening said valve and leaving it in a position where compressed air may pass directly therethrough when applied by the valve 78.

The instant the brakes of the train are applied, the engineer, if alert and not disabled in any manner, is notified by the sudden slowing down of the train that there is an obstruction upon the track ahead, and that caution must be employed in the operation of the train thereafter. If, upon investigation, it is found safe to proceed at a reduced speed, the engineer may do so by operating the valve 78 through the medium of the operating handle 78' thereof and allowing compressed air to pass from the reservoir 75 through the pipe 77, valve 78, pipe 79, reducing valve 80, where the pressure of the air is reduced, valve 82, which is now open, pipe 86 to the cylinder 87 beneath 90 the piston 88. The piston 88 will now immediately be forced upwardly against the action of the spring 91 and the top of the stem 89 will contact with the lower end of the stem 60, forcing the armature 59 95 upwardly a sufficient distance to again close the exhaust valve 69 and again release the brakes. The engineer may, therefore, gradually feel his way along the tracks, so to speak, and gradually move 100 up to the obstruction, but the instant that he shuts off the air from the reservoir 75 the electro-magnet 44 being de-energized, the springs 65 and 66 and spring 91 will force the armature 59 and piston 88 105 respectively downwardly, the air beneath the piston exhausting through the bleed opening 93, and the brakes will again be applied. If, on the other hand, the train or other 110 obstruction ahead and which has caused the break in the electric circuit to the electro-magnet 44 has passed on or been removed thereby again completing the circuit to said electro-magnet 44, when the engineer, through the use of the valve 78 applies the 115 air from the reservoir 75 beneath the piston 88 as previously described, and said piston forces the armature 59 upwardly to the extent of which it is possible, the electro-magnet 44 being now energized and receiving 120 125 130

an electric current from the main feed wires and assisted also by the current generated in the storage battery 46 will immediately attract the armature 59 and therefore 5 after hold said armature and the valves 69 and 82 controlled thereby in the positions illustrated in Fig. 1 and the train may thereafter proceed ahead. If by any accident the connection from the armature 59 to 10 the handle 68 of the valve 69 should become broken, the spring 72 will immediately operate said valve to open the same and allow the air from the train pipe 70 to escape thereby applying the brakes of the train. In 15 like manner if the handle 83 of the valve 82 should become broken or disconnected from the arm 63 of the armature 59 the spring 85 will act to open said valve. When the locomotive is being operated backing up, the 20 switch 41 is thrown from the position illustrated in Fig. 1 where it is in contact with the terminals 40 and 50 to its other position in contact with the terminals 54 and 56, thereby cutting out the shoes 31 and 32 and 25 throwing into operation the shoes 33 and 34 upon the tender. The lights 51 and 57 located in the cab constitute a visible signal to the engineer as to whether there is an obstruction upon the track ahead, as when 30 the same occurs, the circuit is broken and the lights will be extinguished.

As previously stated, when the electro-magnet 44 is energized attracting the armature 59 and closing the valve 69 a port is 35 opened in the valve 82, thereby releasing the air from the pipe 81 and from the pipe 86 leading beneath the piston 88. When this port in the valve 82 is open to the atmosphere by the movement of the armature 40 59, it will allow pressure fluid to escape from the train pipe 71 to the atmosphere if the handle 78' of the valve 78 is in application position, through the pipe 74, reservoir 75, pipe 77, valve 78, pipe 79, reducing valve 45 80, pipe 81 and valve 82, thereby causing another application of the brakes. By this arrangement it will be impossible for an engineer to interfere in any way with the operation or movement of the armature 59 50 and valve 69 when the electric circuit to the electro-magnet 44 is broken.

When the locomotive is running ahead, the electric circuit to the electro magnet 44 is completed from the wire 39, through the 55 shoe 31, rail 8, forward wheels and axle of the locomotive, to the rail 9, shoe 32 and wire 49 and in like manner when the locomotive is running backward, the electric circuit to the electro magnet 44 is completed 60 from the wire 53 through the shoe 33, rail 8, the wheels and axle of the tender which are normally at the rear of said tender, to the rail 9, shoe 34 and wire 55. If it is desired to put the shoes 31 and 32 behind the 65 forward wheels of the locomotive the cut-

out section must be of such length as will not allow said wheels and shoes in said section at the same time. As long as there is power in the rails, the electro magnet 44 will remain energized and 70 the exhaust valve 69 will be held closed. This holds true both in regards to the live sections 10 and 13 and the cut-out sections 11 and 14 but when the electric circuit between the cut-out sections 11 and 14 is 75 broken as at the switch c', the electric circuit upon the locomotive to the electro magnet 44 is broken because the cut-out sections are insulated from the live sections and there is no power in the cut-out sections and 80 the magnet 44 is therefore de-energized thereby opening the valve 69 and applying the brakes upon the train.

I claim:

1. A train control device having, in combination, a main source of electric energy, an electro-magnet upon said train in electric circuit with said main source of electric energy, an auxiliary source of electric energy upon said train and also in electric 90 circuit with said electro-magnet, a train pipe, an exhaust valve for said train pipe, an armature operatively connected with said exhaust valve and adapted to be attracted by said electro-magnet to close said 95 exhaust valve and means rendered effective by the breaking of said electric circuit to open said exhaust valve.

2. A train control device having, in combination, a main source of electric energy, 100 an electro-magnet upon said train in electric circuit with said main source of electric energy, an auxiliary source of electric energy upon said train and also in electric circuit with said electro-magnet, a train 105 pipe, an exhaust valve for said train pipe, an armature operatively connected with said exhaust valve and adapted to be attracted by said electro-magnet to close said exhaust valve and means to force said armature away 110 from said electro-magnet when the electric circuit to the latter is open and thereby open said exhaust valve.

3. A train control device having, in combination, a main source of electric energy, 115 an electro-magnet upon said train in electric circuit with said main source of electric energy, an auxiliary source of electric energy upon said train and also in electric circuit with said electro-magnet, a train 120 pipe, an exhaust valve for said train pipe, an armature operatively connected with said exhaust valve and adapted to be attracted by said electro-magnet to close said 125 exhaust valve, means rendered effective by the breaking of said electric circuit to open said exhaust valve and means independent of said electro-magnet to again close said exhaust valve.

4. A train control device having, in com- 130

- bination, a main source of electric energy, an electro-magnet upon said train in electric circuit with said main source of electric energy, an auxiliary source of electric energy 5 upon said train and also in electric circuit with said electro-magnet, a train pipe, an exhaust valve for said train pipe, an armature operatively connected with said exhaust valve and adapted to be attracted by said electro-magnet to close said exhaust valve, means rendered effective by the breaking of said electric circuit to open said exhaust valve and means actuated by fluid pressure to lift said armature and again close 10 said exhaust valve.
5. A train control device having, in combination, a main source of electric energy, an electro-magnet upon said train in electric circuit with said main source of electric 20 energy, an auxiliary source of electric energy upon said train and also in electric circuit with said electro-magnet, a train pipe, an exhaust valve for said train pipe, an armature operatively connected with said 25 exhaust valve and adapted to be attracted by said electro-magnet to close said exhaust valve, means rendered effective by the breaking of said electric circuit to open said exhaust valve and means to gradually exhaust 30 the fluid escaping through said exhaust valve.
6. A train control device having, in combination, a main source of electric energy, an electro-magnet upon said train in electric 35 circuit with said main source of electric energy, a storage battery upon said train and also in electric circuit with said electro-magnet, a train pipe, an exhaust valve for said train pipe, a casing, an armature slid- 40 ably mounted in said casing and adapted to be attracted by said electro-magnet, means to operatively connect said armature with said exhaust valve, means to positively force said armature away from said electro-magnet when the electric circuit to the latter is 45 open and thereby open said exhaust valve, a cylinder, a piston located within said cylinder and means to operate said piston to lift said armature and again close said exhaust 50 valve.
7. A train control device having, in combination, a main source of electric energy, an electro-magnet upon said train in electric circuit with said main source of electric 55 energy, a storage battery upon said train and also in electric circuit with said electro-magnet, a train pipe, an exhaust valve for said train pipe, a casing, an armature slid- 60 ably mounted in said casing and adapted to be attracted by said electro-magnet, means to operatively connect said armature with said exhaust valve, means to positively force said armature away from said electro-magnet when the electric circuit to the latter is 65 open and thereby open said exhaust valve,
- a cylinder, a piston located within said cylinder, means to operate said piston to lift said armature and again close said exhaust valve and means to automatically open said exhaust valve if the latter becomes operatively disconnected from said armature. 70
8. A train control device having, in combination, a main source of electric energy, an electro-magnet upon said train in electric circuit with said main source of electric 75 energy, a storage battery upon said train and also in electric circuit with said electro-magnet, a train pipe, an exhaust valve for said train pipe, an armature operatively connected with said electro-magnet to close 80 said exhaust valve, means to force said armature away from said magnet when the electric circuit to the latter is open and thereby open said exhaust valve, a cylinder, a piston located within said cylinder and 85 means to operate said piston to lift said armature and again close said exhaust valve.
9. A train control device having, in combination, a main source of electric energy, an electro-magnet upon said train in electric 90 circuit with said main source of electric energy, a storage battery upon said train and also in electric circuit with said electro-magnet, a train pipe, an exhaust valve for said train pipe, an armature operatively 95 connected with said electro-magnet to close said exhaust valve, means to force said armature away from said magnet when the electric circuit to the latter is open and thereby open said exhaust valve, a cylinder, a fluid pressure reservoir connected with said train pipe and means to conduct pressure fluid from said reservoir to said cylinder beneath said piston to lift said armature and again 100 close said exhaust valve.
10. A train control device having, in combination, a main source of electric energy, an electro-magnet upon said train in electric circuit with said main source of electric 110 energy, a storage battery upon said train and also in electric circuit with said electro-magnet, a train pipe, an exhaust valve for said train pipe, an armature operatively connected with said electro-magnet to close 115 said exhaust valve, means to force said armature away from said magnet when the electric circuit to the latter is open and into a position out of the area of influence of said magnet, thereby opening said exhaust valve 120 and means to lift said armature to again close said exhaust valve.
11. A train control device having, in combination, a main source of electric energy, an electro-magnet upon said train in electric 125 circuit with said main source of electric energy, a storage battery upon said train and also in electric circuit with said electro-magnet, a train pipe, an exhaust valve for said train pipe, an armature operatively con- 130

nected with said electro-magnet to close said exhaust valve, means to force said armature away from said magnet when the electric circuit to the latter is open and into a position 5 out of the area of influence of said magnet, thereby opening said exhaust valve, means to lift said armature to again close said exhaust valve and also to position said armature to again be attracted by said electro-magnet when the electric circuit to the latter 10 is again closed.

12. A train control device having, in combination, a main source of electric energy, an electro-magnet upon said train in electric circuit with said main source of electric energy, an auxiliary source of electric energy upon said train and also in electric circuit with said electro-magnet, a train pipe, a discharge cylinder connected with said train 15 pipe, and provided with discharge ports therein, a spring actuated piston within said cylinder, an exhaust valve located between said cylinder and said train pipe, an armature operatively connected with said exhaust 20 valve and means rendered effective by the breaking of said electric circuit to force said armature away from said magnet and thereby open said exhaust valve whereby a fluid within said train pipe is admitted to said discharge cylinder depressing said piston, said fluid being gradually discharged 25 through the ports of said cylinder.

13. A train control device having, in combination, a main source of electric energy, an electro-magnet upon said train in electric circuit with said main source of electric energy, a storage battery upon said train and also in electric circuit with said electro-magnet, a train pipe, an exhaust valve for 30 said train pipe, an armature operatively connected with said electro-magnet to close said exhaust valve, means to force said armature away from said magnet when the electric circuit to the latter is open and thereby open 35 said exhaust valve, a cylinder, a piston located within said cylinder, a fluid pressure reservoir connected with said train pipe, means to conduct pressure fluid from said reservoir to said cylinder beneath said piston to lift said armature and again close said 40 exhaust valve and means to control the flow of fluid to said cylinder.

14. A train control device having, in combination, a main source of electric energy, an electro-magnet upon said train in electric circuit with said main source of electric energy, a storage battery upon said train and also in electric circuit with said electro-magnet, a train pipe, an exhaust valve for 45 said train pipe, an armature operatively connected with said electro-magnet to close said exhaust valve, means to force said armature away from said magnet when the electric circuit to the latter is open and thereby open 50 said exhaust valve, a cylinder, a piston located within said cylinder, a fluid pressure reservoir connected with said train pipe, means to conduct pressure fluid from said reservoir to said cylinder beneath said piston to lift said armature and again close said 55 exhaust valve and means to control the flow of fluid to said cylinder.

cated within said cylinder, a fluid pressure reservoir connected with said train pipe, means to conduct pressure fluid from said reservoir to said cylinder beneath said piston to lift said armature and again close said 60 exhaust valve, means to control the flow of fluid to said cylinder and means to regulate the pressure of the fluid delivered to said cylinder.

15. A train control device having, in combination, a main source of electric energy, an electro-magnet upon said train in electric circuit with said main source of electric energy, a storage battery upon said train and also in electric circuit with said electro-magnet, a train pipe, an exhaust valve for 65 said train pipe, an armature operatively connected with said electro-magnet to close said exhaust valve, means to force said armature away from said magnet when the electric circuit to the latter is open and thereby open 70 said exhaust valve, a cylinder, a piston located within said cylinder, a fluid pressure reservoir connected with said train pipe, means to conduct pressure fluid from said reservoir to said cylinder beneath said piston to lift said armature and again close said 75 exhaust valve, means to control the flow of fluid to said cylinder, means to regulate the pressure of the fluid delivered to said cylinder and means to release the pressure within 80 said cylinder beneath said piston.

16. A train control device having, in combination, a main source of electric energy, an electro-magnet upon said train in electric circuit with said main source of electric energy, a storage battery upon said train and also in electric circuit with said electro-magnet, a train pipe, an exhaust valve for 85 said train pipe, an armature operatively connected with said electro-magnet to close said exhaust valve, means to force said armature away from said magnet when the electric circuit to the latter is open and thereby open 90 said exhaust valve, a cylinder, a piston located within said cylinder, a fluid pressure reservoir connected with said train pipe, means to conduct pressure fluid from said reservoir to said cylinder beneath said piston to lift said armature and again close said 95 exhaust valve, means to control the flow of fluid to said cylinder, means to regulate the pressure of the fluid delivered to said cylinder and means to release the pressure within 100 said cylinder beneath said piston.

17. A train control device having, in combination, a main source of electric energy, an electro-magnet upon said train in electric circuit with said main source of electric energy, a storage battery upon said train and also in electric circuit with said electro-magnet, a train pipe, an exhaust valve for 105 said train pipe, an armature operatively connected with said electro-magnet to close said exhaust valve, means to force said armature away from said magnet when the electric circuit to the latter is open and thereby open 110 said exhaust valve, a cylinder, a piston located within said cylinder, a fluid pressure reservoir connected with said train pipe, means to conduct pressure fluid from said reservoir to said cylinder beneath said piston to lift said armature and again close said 115 exhaust valve, means to control the flow of fluid to said cylinder, means to regulate the pressure of the fluid delivered to said cylinder and means to release the pressure within 120 said cylinder beneath said piston.

18. A train control device having, in combination, a main source of electric energy, an electro-magnet upon said train in electric circuit with said main source of electric energy, a storage battery upon said train and also in electric circuit with said electro-magnet, a train pipe, an exhaust valve for 125 said train pipe, an armature operatively connected with said electro-magnet to close said exhaust valve, a cylinder, a piston located within said cylinder, a fluid pressure reservoir connected with said train pipe, means to conduct pressure fluid from said reservoir to said cylinder beneath said piston to lift said armature and again close said 130 exhaust valve, means to control the flow of fluid to said cylinder, means to regulate the pressure of the fluid delivered to said cylinder and means to release the pressure within said cylinder beneath said piston.

valve, means to force said armature away from said magnet when the electric circuit to the latter is open and thereby open said exhaust valve, a cylinder, a piston located 5 within said cylinder, a fluid pressure reservoir connected with said train pipe, means to conduct pressure fluid from said reservoir to said cylinder beneath said piston to lift said armature and again close said exhaust valve, 10 means to control the flow of fluid to said cylinder, means to regulate the pressure of the fluid delivered to said cylinder and a valve located within said fluid pressure conducting means and operatively connected with said 15 armature and adapted to automatically release the pressure within said cylinder beneath said piston.

18. A train control device having, in combination, a main source of electric energy, an 20 electro-magnet upon said train in electric circuit with said main source of electric energy, a storage battery upon said train and also in electric circuit with said electro-magnet, a train pipe, an exhaust valve for said 25 train pipe, an armature operatively connected with said electro-magnet to close said exhaust valve, means to force said armature away from said magnet when the electric circuit to the latter is open and thereby open 30 said exhaust valve, a cylinder, a piston located within said cylinder, a fluid pressure reservoir connected with said train pipe, means to conduct pressure fluid from said reservoir to said cylinder beneath said piston to lift said armature and again close said exhaust valve, means to control the flow of fluid to said cylinder, means to regulate the 35 pressure of the fluid delivered to said cylinder and a valve located within said fluid pressure conducting means and operatively connected with said armature adapted to automatically release the pressure within said cylinder beneath said piston and means independent of said armature to operate said 40 last-named valve to open the passage therethrough.

19. A train control device having, in combination, a main source of electric energy, an 45 electro-magnet upon said train in electric circuit with said main source of electric energy, an auxiliary source of electric energy upon said train and also in electric circuit with said electro-magnet, a pair of contact shoes upon said train in electric circuit with said electro-magnet and auxiliary source of electric energy, a second pair of contact shoes upon said train connected with said main source of electric energy but disconnected from said electro-magnet and auxiliary source of electric energy, an electric 55 switch upon said train in electric circuit with said electro-magnet and auxiliary source of electric energy whereby the main source of electric energy may be received by the 60 electro-magnet from either of said pair of

contact shoes, a train pipe, an exhaust valve for said train pipe, an armature operatively connected with said exhaust valve and adapted to be attracted by said electro-magnet to close said exhaust valve and means 70 to force said armature away from said electro-magnet when the electric circuit to the latter is open and thereby open said exhaust valve.

20. A train control device comprising a 75 railway track embodying therein a plurality of live sections and a plurality of cut-out sections insulated from said live sections, an electric circuit including an electro-magnet for each live section, an electric circuit 80 including an electric switch for each cut-out section, the switch of each cut-out section being operated by the electro-magnet of a live section, a train pipe, an exhaust valve for said train pipe, an electric circuit 85 including the rails of said railway track and extending to and including a storage battery and an electro-magnet located upon said train and means rendered effective by the breaking of said last-named electric circuit 90 to open said exhaust valve.

21. A train control device comprising a railway track embodying therein a plurality of live sections and a plurality of cut-out sections insulated from said live sections, an 95 electric circuit including an electro-magnet for each live section, an electric circuit including an electric switch for each cut-out section, the switch of each cut-out section being operated by the electro-magnet of a live section, a train pipe, an exhaust valve for said train pipe, an electric circuit including the rails of said railway track and extending to and including a storage battery and an electro-magnet located upon said train, means rendered effective by the breaking of said last-named electric circuit to open said exhaust valve and means to gradually exhaust the 100 fluid escaping through said exhaust valve.

22. A train control device comprising a 110 railway track embodying therein a plurality of live sections and a plurality of cut-out sections insulated from said live sections, an electric circuit including an electro-magnet for each live section, an electric circuit including an electric switch for each cut-out section, the switch of each cut-out section being operated by the electro-magnet of a live section, a train pipe, an exhaust valve for said train pipe, an electric circuit including 115 the rails of said railway track and extending to and including a storage battery and an electro-magnet located upon said train, an armature operatively connected with said exhaust valve and adapted to be attracted by 120 said last-named electro-magnet to close said exhaust valve and means to force said armature away from said magnet when the electric circuit to the latter is broken and thereby open said exhaust valve.

23. A train control comprising a railway track embodying therein a plurality of live sections and a plurality of cut-out sections insulated from said live sections, an electric circuit including an electro-magnet for each live section, an electric circuit including an electric switch for each cut-out section, the switch of a cut-out section being operated by the electro-magnet of a live section, a 10 train pipe, an exhaust valve for said train pipe, an electric circuit including the rails of said railway track and extending to and including a storage battery and an electro-magnet located upon said train, an armature operatively connected with said exhaust valve and adapted to be attracted by said last-named electro-magnet to close said exhaust valve, means to force said armature away from said magnet when the electric circuit to the latter is broken and thereby open said exhaust valve and means independent of said last-named electro-magnet to again close said exhaust valve.

24. A train control device comprising a railway track embodying therein a plurality of live sections and a plurality of cut-out sections insulated from said live sections, an electric circuit including an electro-magnet for each live section, an electric circuit including an electric switch for each cut-out section, the switch of a cut-out section being operated by the electro-magnet of a live section, a train pipe, an exhaust valve for said train pipe, an electric circuit including the rails of said railway track and extending to and including a storage battery and an electro-magnet located upon said train, an armature operatively connected with said exhaust valve and adapted to be

attracted by said last-named electro-magnet 40 to close said exhaust valve, means to force said armature away from said magnet when the electric circuit to the latter is broken and thereby open said exhaust valve and means actuated by fluid pressure to again close said 45 exhaust valve.

25. A train control device comprising a railway track embodying therein a plurality of live sections and a plurality of cut-out sections insulated from said live sections, an electric circuit including an electro-magnet for each live section, an electric circuit including an electric switch for each cut-out section, the switch of a cut-out section being operated by the electro-magnet of a live section, a train pipe, an exhaust valve for said train pipe, an electric circuit including the rails of said railway track and extending to and including a storage battery and an electro-magnet located 50 upon said train, an armature operatively connected with said exhaust valve and adapted to be attracted by said last-named electro-magnet to close said exhaust valve, means to force said armature away from said magnet when the electric circuit to the latter is open and thereby open said exhaust valve, a cylinder, a piston located within said cylinder and means to operate said piston to lift said armature and again 55 close said exhaust valve.

In testimony whereof I have hereunto set my hand in presence of two subscribing witnesses.

GEORGE H. SANBORN.
